INVENTOR
Paul C. Smalley
BY
Fred C. Fischer
ATTORNEY

UNITED STATES PATENT OFFICE.

PAUL C. SMALLEY, OF NEWARK, NEW JERSEY.

FLASHLIGHT DEVICE.

1,376,976.

Specification of Letters Patent.

Patented May 3, 1921.

Application filed January 13, 1920. Serial No. 351,109.

To all whom it may concern:

Be it known that I, PAUL C. SMALLEY, a citizen of the United States, residing in the city of Newark, in the county of Essex and State of New Jersey, have invented certain new and useful Improvements in Flashlight Devices, of which the following is a full, clear, and exact description, such as will enable others skilled in the art to which it pertains to make, construct, and use the same, reference being had to the accompanying drawings, and to numerals of reference marked thereon, forming a part of this specification.

15 The present invention relates to battery hand lamps or flash lights of a type adapted for carrying in the pocket and provided with a miniature lamp of which current may be delivered from a battery inclosed in the casing of the device. It has been found in practice that when these hand lamps are dropped there is danger that the batteries will crash through the base of the incandescent lamp and destroy it, and this is particularly the case when the battery is supported at its base on a coiled contact spring, for the spring permits enough movement of the battery in the case to give a relatively heavy blow when the battery strikes the lamp at the other end of the case. In many hand lamps of usual construction there is also danger of crushing the lamp by screwing on the bottom cap of the device so tightly as to crowd the batteries forcibly against the base of the lamp.

30

35

The object of my invention is characterized by the provision of means secured to the threaded portion of the reflector, interposed between the same and the batteries in such a way as to take the direct thrust of the batteries thereby preventing the destruction of the incandescent lamp.

A further object of my invention is to provide a device which will adapt itself to most of the commercial battery hand lamps on the market today, and which is exceedingly simple and effective in construction, comparatively inexpensive in cost and durable in use.

50 While the preferred forms of my invention

are illustrated in the accompanying drawings, yet it is to be understood that minor changes may be made without departing from the scope thereof.

In the drawings,

Figure 1 represents a cross section through an embodiment of my invention, illustrating the batteries and lamp in elevation.

Figs. 2 and 3 represent, respectively, a side and a plan view of the same.

Figs. 4 and 5 represent, respectively, a front and a side elevation of a modified form of my improved device.

Figs. 6 and 7 represent detail views of the same; and

Figs. 8 and 9 represent side elevations of other modified forms of my improved device.

Similar characters of reference are employed in all of the above described views to indicate corresponding parts.

Referring now to the drawings, the reference character 1 indicates a metallic tubular casing containing the cylindrical batteries 2, though, of course, this casing may be of any convenient form, or other suitable material.

3 represents a screw-threaded closure having screw-threaded engagement with the bottom of the casing 1, wherein a coiled spring 4 is seated for contacting with the zinc electrode of one of the batteries.

The upper end of the casing 1 is preferably screw-threaded to receive a screw-threaded annular member 5 folded or spun at 6 over the edge of the lens 7.

8 represents a reflector having a central opening, into which the lamp socket 9 of the lamp 10 is mounted, the base part 11 of the lamp forms one of the poles, the other pole being shown at 12.

When mounted in the casing 1, one pole of the battery is connected to the casing through the spring 4, as described, and the other pole 13 of the battery is connected to the terminal 12 of the lamp, leaving the circuit between the reflector and the casing 1 open. Suitable means are provided to close this gap in the circuit when it is desired to operate the lamp, and said means here

shown consists of a movable member 14, which engages the casing through contact therewith, and which is slidable in said casing to engage the reflector 8. The end 15 of the movable member 14 being turned up to form a sliding contact with the reflector, so as to insure a bright surface, due to the rubbing of the end 15 over the reflector 8, and thereby a good contact.

10 Suitable means, for operating the member 14 are provided, which consists of a slideable finger piece 16 connected to said member 14 and secured to the casing 1 as is well-known.

15 The means for preventing the destruction of the incandescent lamp consists essentially of an apertured disk 17, which may be made of wood, fiber, hard rubber or any suitable material.

20 The apertured portion of the disk is screw-threaded to receive the screw-threaded portion of the reflector 8.

The under side of the disk is provided with an offset portion as at 18 over which 25 the open end of the metallic cap 19 is forced thus securing the two parts together.

One side of the metallic cap 19 is pierced as at 20 to provide a tongue 21 projecting inwardly into the shell, the end of which is 30 designed to contact with the lamp terminal 12, to insure good electrical contact with the battery terminal end with said lamp terminal.

In the modified forms illustrated in Figs. 35 4, 5, 6 and 7 of the drawings, it will be noticed that I have dispensed with the metallic shell 19 and substituted therefor the metallic contact member 22, which in its preferred form is made from flat strip metal 40 and provided with an annular portion 23 designed to be secured to the annular shoulder 18 of the disk 17. Extending integrally from the annular portion 23 is the downwardly, outwardly, upwardly, and inwardly extending portion 24, the outwardly and inwardly extending portions 24 thereof insuring good electrical contact with the battery and lamp terminals.

In the modified forms illustrated in Figs. 50 8 and 9 of the drawings, it will be noticed that I have dispensed with the apertured member of insulating material and provided a shock absorber made from a single piece of contact making material.

55 In Fig. 8, the device consists of a spiral spring 25 preferably of conical shape, the upper portion of which is designed to engage with the pole 12 of the lamp and the lower portion designed to engage with and 60 encircling the pole 13 of the battery thereby establishing electrical connections.

In Fig. 9 of the drawings the device consists essentially of a metallic member 26 preferably made from a single strip of suit-

able material one end of which is enlarged 65 and provided with a struck up hollow head 27 designed to receive the pole 13 of the battery and the opposite free end thereof designed to engage with the pole 12 of the lamp, the intermediate portion of the strip 70 being bent as clearly indicated in the drawings, thereby establishing electrical connections.

In both of these cases the device is positioned upon the pole 13 of the battery and 75 held thereon against accidental displacement.

I am aware that some changes may be made in the details of construction of the parts of the device, without departing from 80 the scope of my present invention, hence I do not limit my invention to the exact details of construction of the various parts thereof.

Having thus describe my invention, what 85 I desire to secure by Letters Patent is:—

1. A flash light comprising a casing, a battery therein, means pressing against the bottom of said battery to establish electrical connection therewith, a lens and a reflector 90 at the other end of said casing, a lamp secured in said reflector, a shock absorber comprising an apertured disk carried by said reflector and a metallic shell secured to said disk to receive the thrust of said battery, said shell provided with an inwardly extending tongue, said shell and tongue directly connecting one terminal of said battery to said lamp and means for completing the connections between said bottom spring 100 and said lamp.

2. A flash light comprising a casing, a battery therein, means pressing against the bottom of said battery to establish electrical connections therewith, a lens and a reflector 105 at the other end of said casing, a lamp secured in said reflector, a shock absorber comprising an insulating member carried by said reflector and a metallic member carried by said insulating member to receive the thrust of said battery, said metallic member directly connecting one terminal of said battery to said lamp and means for completing the connections between said bottom spring 110 and said lamp.

3. A flash light comprising a casing, a battery therein, means pressing against the bottom of said battery to establish electrical connections therewith, a lens and a reflector at the other end of said casing, a lamp secured in said reflector, a shock absorber comprising an apertured insulating disk having screw-threaded engagement with said reflector, and metallic contact making means made from a single piece of suitable material carried by said disk to receive the thrust of said battery and directly connecting one terminal of said battery to said

lamp and means for completing the connections between the bottom spring and said lamp.

4. As a new article of manufacture, a removable shock absorber for use in flash lights, comprising an apertured member of insulating material carried by the flash light reflector and metallic contact making and shock absorbing means carried by said

member designed to directly connect one terminal of the flash light battery to the flash light lamp.

This specification signed and witnessed this 11th day of January, 1920.

PAUL C. SMALLEY.
